UNITED STATES PATENT OFFICE

2,071,863

TRAFFIC GUARD

George A. Gleason, Worcester, Mass., assignor to
 The American Steel and Wire Company of New
 Jersey, a corporation of New Jersey

Application March 6, 1934, Serial No. 714,319

4 Claims. (Cl. 256—13.1)

This invention relates to traffic guards, and more particularly those which are installed along highways, although not limited thereto.

One object of the present invention is the provision of a novel traffic guard which will very effectively resist heavy impact forces, but one which will at the same time be very cheap and easy to manufacture and install.

Another object is to provide a device of the class described which will be resiliently deformable laterally, longitudinally and vertically with respect to its supporting structure, and preclude the possibility of shearing its connecting devices, such as nuts, bolts and the like.

15 A still further object of the invention is to provide a novel traffic guard which will be more easily discernible than the devices of the prior art.

These and further objects will be apparent after referring to the drawings, in which:

20 Figure 1 is a side elevation of the device of the invention.

Figure 2 is a sectional end elevation.

Figure 3 is a sectional plan.

25 Figures 4 through 7 are sectional plans of various modified forms of the invention.

Referring more particularly to the drawings, the numeral 2 designates a plurality of a conventional type of post which is particularly adaptable for supporting the devices of the invention, although it is to be understood that they may, in practice, be any of a number of well known designs. The fence posts 2 are provided with apertures 3 at spaced intervals.

30 A plurality of novel resiliently deformable elements are provided for connecting the guard of the invention to the posts 2 and each comprises broadly a substantially oval-shaped sleeve 4 having enlarged and rearwardly curved portions 5 at either of its ends. The substantially oval-shaped sleeves 4 may be made of any suitable metal, and are preferably not continuous, having their ends overlapped on one of their sides, as shown at 6. The sides of the oval-shaped sleeves 4 which are opposite the overlapped ends 6 are apertured, as at 7, to permit a bolt 8 to extend therethrough, and through the apertures 3 in the posts 2. A lock washer 9 and nut 10 are provided on the inner side of each of the posts 2 for securing the sleeves 4 in rigid position. The overlapping ends 6 on the sides of the substantially oval-shaped sleeves 4 are apertured, as at 12.

35 The novel guard of the invention comprises a flexible metallic strip 14 of substantial width, which is suitably apertured at intervals conforming to the linear spacing of the posts 2, as shown

5 at 15. A washer 16 is provided for the outer side of the strip 14 and comprises a beveled strip having a plurality of spaced and countersunk apertures. A bolt 17 is extended inwardly through each of the countersunk apertures in the washer 16 through each of the apertures 15, in the strip 14, and through the apertures 12 in the overlapped ends 6 of the substantially oval-shaped sleeves 4, and each receives a lock washer 19 and nut 20 on its threaded end.

10 Referring to Figure 4 of the drawings, the substantially oval-shaped sleeve 4 is provided, as in the preferred embodiment, with rearwardly curved, enlarged portions 5, but its ends 6 are overlapped on the opposite side thereof from that 15 shown therein.

15 A still further modification of the substantially oval-shaped sleeve 4 contemplates the provision of curved and reduced extensions 5a which extend rearwardly in lieu of the enlarged curved portions 5, as shown in Figure 5.

20 In Figure 6 the substantially oval-shaped sleeve 4, of Figure 4, is shown as provided with a reinforcing spring 22 having an aperture 23 which is adapted to align with the apertures 12 in the overlapped ends 6. The spring 22 carries forwardly curving extensions 24, with oppositely curved portions 25 on its ends for contacting that portion of the sleeve 4 which is adjacent the metallic strip 14.

25 In Figure 7 of the drawings, a still further modification contemplates a metallic sleeve composed partially of a curved plate 27, having oppositely curved portions 28 on its ends, and being apertured along its mid-portion as at 29. 30 A curved plate 30 is arranged with its axis extending oppositely with respect to the axis of the curved plate 27, and is secured to the ends of the oppositely curved portions 28 of the latter by way of being bent thereover, as at 31.

35 In installing the device of the invention, and using any of the substantially oval-shaped flexible sleeves heretofore described, the upper portions of the posts 2 are apertured, as at 33, for receiving the ends of a U-bolt 34 which is adapted 40 to be secured thereto by means of the usual nuts 35. A guard cable 36 is strung between the U-bolt 34 in a taut manner before the nuts 35 are tightened, which permits the distribution of impact forces between a number of the posts 2 45 independently of the metallic strip 14.

50 Due to the ability of the resiliently deformable sleeves to receive impact forces laterally, longitudinally and vertically with respect to the posts 2, the possibility of the shearing of the various 55

bolts 8 and 17 is eliminated, and the substantial width of the strip 14 makes it much more readily discernible to those using the highway than any of the devices of which I am aware.

5 While I have shown and described several specific embodiments of my invention, it will be understood that I do not wish to be limited exactly thereto, since various modifications may be made without departing from the scope of my 10 invention, as defined in the following claims.

I claim:

1. A highway traffic guard comprising a plurality of spaced posts arranged along the edge of the highway, a vertically disposed resiliently 15 compressible metallic sleeve supported by at least one of said posts, a flexible metallic strip of substantial width extending horizontally across the outer surface of said sleeve in spaced relation to said supporting post, a strip extending vertically 20 across the outer surfaces of said flexible metallic strip, and connecting means extending through both of said strips.

2. A highway traffic guard comprising a plurality of spaced posts arranged along the edge of the highway, a vertically disposed resiliently 25 compressible metallic sleeve supported by at least one of said posts, a flexible metallic strip of substantial width extending horizontally across the outer surface of said sleeve in spaced relation to said 30 supporting post, a beveled strip extending verti-

cally across the outer surface of said flexible metallic strip, and connecting means extending through both of said strips.

3. A highway traffic guard comprising a plurality of spaced posts arranged along the edge of the highway, a vertically disposed resiliently 5 compressible metallic sleeve supported by at least one of said posts, a flexible metallic strip of substantial width extending horizontally across the outer surface of said sleeve in spaced relation to said 10 supporting post, a strip extending vertically across the outer surface of said flexible metallic strip, connecting means extending through both of said strips and means within said sleeve for resisting the compression thereof. 15

4. A highway traffic guard comprising a plurality of spaced posts arranged along the edge of the highway, a vertically disposed resiliently compressible metallic sleeve supported by at least one of said posts, a flexible metallic strip of substantial width extending horizontally across the outer surface of said sleeve in spaced relation to said supporting post, a strip extending vertically across the outer surface of said flexible metallic strip, connecting means extending through both of said strips and means within said sleeve for resisting the compression thereof, said means 20 being connected to said supporting post. 25

GEORGE A. GLEASON. 30
